CIRCUIT INTERRUPTER

Herbert L. Rawlins, Wilkinsburg, Pa., assignor to
Westinghouse Electric & Manufacturing Com-
pany, East Pittsburgh, Pa., a corporation of
Pennsylvania

Application August 25, 1933, Serial No. 686,760

19 Claims. (Cl. 200—123)

My invention relates to circuit interrupters and particularly to high voltage explosion fuses.

One object of my invention is to provide a refillable high voltage explosion fuse that shall be simple in design, more economical to manufacture, and more satisfactory and reliable in operation than the previously known devices of this type.

Another object of my invention is to provide an improved refill element for use with explosion fuses, my improved refill element to be inexpensive to manufacture and simple to install.

A further object of my invention is to provide an improved high voltage explosion fuse which shall include at least two separate arc passages and means for establishing an arc in each of the passages, the arc interrupting capacity of the two passages being different in order that the fuse may be equally effective for both high and low values of arc current.

A further object of my invention is to provide an improved circuit interrupter wherein a biased contact member is held against its biasing force by a fusible element which possesses considerable mechanical strength but which is fusible upon the occurrence of relatively moderate overloads to permit the biasing means to cause the opening of the interrupter.

A further object of my invention is to provide an improved high voltage explosion fuse which shall utilize a fusible element having sufficiently large physical dimensions to prevent any injury thereto as a result of corona formation, and which shall, at the same time, be operable to effect the opening of the controlled circuit when relatively low magnitude currents flow therethrough.

A further object of my invention is to provide an improved fusible element for use with electrical apparatus. My improved fusible element to have sufficient thermal capacity to prevent the operation thereof upon the occurrence of transient overloads of large magnitude and to be operable upon the occurrence of continued overloads of small magnitude.

A further object of my invention is to provide an improved circuit interrupter which shall be operable upon the actuation of thermally responsive means which includes a current carrying heater and means for increasing the normal heating effect of the heater upon the occurrence of predetermined conditions.

A still further object of my invention is to provide an improved explosion fuse structure which shall include a means for closing one end of the fuse tube and electro-responsive means for opening that end of the fuse tube upon the occurrence of predetermined conditions.

One field for immediate application of my invention is in connection with high voltage po-

tential transformer fuses that utilize boric acid as the source of arc extinguishing gas, and I shall hereinafter describe an embodiment of my invention as applied to such devices without, however, in any way intending to restrict the scope of my invention except as indicated in the appended claims.

In this type of fuse, a short fusible link is connected to the lower end of a movable rod or plunger, the other end of the rod being affixed to a piston member of conducting material which is disposed within an insulating tube and is biased upwardly by a coil spring. A flexible conducting shunt disposed within the coil spring completes the electrical circuit to the stationary contact. Upon the fusing of the link, the rod moves upwardly under the influence of a biasing spring and establishes the arc within a chamber that is lined with boric acid. The boric acid being decomposed and the resulting outwardly flowing vapor, substantially all of which is superheated steam, extinguishes the arc.

The fuse is restored to an operative condition following each circuit interrupting operation by the removal and replacement of the refill element which includes the boric acid lining for the arc passage, the movable plunger, and the fuse assemblage. From this, it is immediately apparent that the refill operation consists in the replacing of all of the parts which are subjected to the action of the arc, thereby continuing reliable operation of the device.

The fusible element which is used in this type of circuit interrupter is subjected to very exacting operating requirements. In order to secure satisfactory operation of the fuse, it is necessary that the plunger be moved at a comparatively rapid rate thus necessitating the use of a relatively powerful actuating spring. The entire force of this spring must be opposed by the fusible link itself and at the same time, the link must be capable of fusing when relatively low current flows therethrough. This last requirement is particularly important in circuits such as potential transformer circuits wherein the maximum current carried usually does not exceed one-half ampere. Thus, the fusible link must have considerable mechanical strength, it must be capable of opening the circuit when comparatively low magnitude currents flow therethrough, and at the same time, it must have sufficient physical dimensions to prevent any injury thereto as a result of corona formation.

Heretofore there has been no satisfactory means for accomplishing these requirements and consequently entirely no satisfactory high voltage fuse has been available for use on circuits having a normal line current of less than 5 amperes. A fuse embodying the features of my invention, however, meets all of these requirements

and permits the satisfactory operation of a high voltage fuse upon overload currents as low as one-tenth ampere, this increased range of satisfactory operation being made possible by the 5 novel means which I employ for causing the fusing of the link which holds the movable plunger in the closed circuit position against the spring biasing means.

The features of my invention which I believe 10 to be new are particularly pointed out in the appended claims. For a fuller understanding of those principles and the best mode of applying the same, reference may be had to the accompanying drawing, in which

15 Figure 1 is a side elevational view, partially in section, of an expulsion fuse embodying the principal features of my invention.

Fig. 2 is an enlarged sectional view of a refill element for use with the expulsion fuse shown 20 in Fig. 1.

Fig. 3 is a fragmentary sectional view similar to Fig. 2 showing a modified form of refill unit.

Figs. 4 and 5 are end elevations of the refill unit shown in Fig. 2.

25 Fig. 6 is an enlarged detailed view of the plunger assemblage shown in Figs. 1 and 2, and

Figs. 7, 8 and 9 are detail views showing the improved heating device utilized in this embodiment of my invention.

30 The expulsion fuse shown in Fig. 1 includes a cylindrical fibre tube 1, having relatively heavy side walls and threaded ends 3 and 5, and two tubular terminal members 7 and 9 of conducting material which have threaded portions 11 35 and 13, respectively, for engaging the threaded ends 3 and 5 of the main fibre tube 1. The outer surface of each of the terminal members 7 and 9, which are substantially cylindrical in form, is utilized for engaging suitable contact jaws (not 40 shown). The upper terminal member 7 is provided with a second internally threaded portion 15 for engaging an annular member 17 which is utilized for supporting one end of the operating spring 19. The upper end of the fuse 1 is 45 closed by means of a cap member 21 having a threaded internal portion 23 which cooperates with a similarly threaded portion 25 on the upper support member 27 for the operating spring 19.

The working parts of the fuse include the 50 main operating spring 19, one end of which engages a threaded portion 29 on the upper support member 27, the flexible conducting shunt 31 disposed within the main operating spring 19 and electrically connected to the upper spring 55 supporting member 27 and the piston member 33 by means of suitable screws 35, and the refill element 37 which engages the piston member 33. The lower end of the operating spring 19 engages a threaded portion 39 on the piston member in 60 substantially the same manner that the upper end engages the support member 27.

The preferred form of the refill element 37 is shown particularly in Fig. 2. It includes a fibre tube 41, having side walls of considerable 65 mechanical strength and a threaded end 42 for engaging the threaded metallic ferrule 44. The fibre tube 41 is lined for the greater part of its length with a cylindrical lining member 43 composed of compressed boric acid. The boric acid 70 lining 43 has a cylindrical passage 45, through the central portion thereof for accommodating the rod or plunger 47, and is further provided with a second passage 49 extending therethrough of considerably smaller cross sectional area than the 75 central passage 45.

A threaded fibre plug 51 having an opening 53 therethrough is provided for engaging the upper end of the boric acid lining 43. The lower end of the central passage 45 terminates in a conical throat 55, the lower portion of which is defined 5 by a fibre plug 57, it being desirable to provide material of greater mechanical strength than boric acid for lining those portions of the arc passage where the thickness of the lining becomes small. The ferrule 44 has a threaded portion 59 for engaging the threaded end 42 of the fibre tube 41 and is provided with an annular shoulder 61 for engaging the end of the fibre plug 57. The central opening 63 through the ferrule 44 forms a continuation of the central passage 45 15 and the throat 55.

The cylindrical plunger or rod member 47 is preferably constructed of copper; the lower end has a slotted opening 65 therein for engaging one end of the flat fusible strip 67, a soft metal 20 rivet 69 being provided for rigidly affixing the fusible element 67 thereto. The other end of the fusible link 67 is soldered within a slot 73 in the copper rivet 71, which is adapted to engage the disk member 75 to hold the plunger 47 against 25 movement under the biasing influence of the spring 19. The disk member in turn abuts against the annular shoulder 61 in the ferrule 44 of the refill element.

The upper end 77 of the plunger rod 47 is 30 threaded for engaging the piston member 33, and is provided with a positioning pin 79 extending therethrough substantially at right angles to the longitudinal axis of the plunger. This pin, as is shown particularly in Figs. 2 and 4, cooperates 35 with two diametrically opposed slots 81 in the top portion of the fibre tube 41 of the refill unit in order to prevent rotation of the plunger with respect to the other parts of the refill unit during the refilling operation.

In both forms of refill unit, a wire 83, of 40 somewhat smaller cross sectional area than the cross sectional area of the smaller passage 49 through the boric acid lining 43, is securely affixed to the upper end of the plunger rod 47 45 and extends down into the smaller passage 49 where it slidably engages a similar wire 85 extending upwardly into the smaller passage for about one-third of its length. The lower end of the wire 85 is retained in position within a 50 recess 87 in the fibre throat member 57.

The retaining disk member 75 which is utilized 55 for holding the plunger member 47 against the biasing force of the operating spring 19 is shown particularly in Figs. 7, 8 and 9. The disk 75 is 60 preferably constructed of a non-metallic resistance material such as carbon or carborundum, and is provided with a central opening 89 to permit the passage therethrough of the shank portion of the rivet 71, and a pair of annular 65 metal portions 91 and 93 electroplated thereon. The outer plated portion 91 is adapted to engage the annular shoulder 61 on the ferrule 44 in order to provide a good electrical connection between the disk and the ferrule, and the inner plated portion 93 is adapted to engage the plunger retaining rivet 71. The disk 75 is used for supplying heat to the retaining rivet 71 in order to cause the fusion of the fusible link 67 which is soldered in the slot 73 therein. This arrangement is most 70 suitable for use on very low current circuits, due to the fact that the disk itself possesses considerable inherent resistance to the flow of an electric current; it does permit, however, very accurate calibration of the device.

I prefer to use one of the lead bismuth alloys, the proportions of which closely approximate those of the eutectic alloy of those metals, for the fusible link 67. These alloys have very sharp melting points, usually in the neighborhood of 80 to 120° C., and permit very close calibration of the thermally responsive element.

In the modification shown in Fig. 3, the resistance disk is paralleled by a second fusible element 95 soldered at one end to the ferrule 44 and at the other to the retaining rivet 71. This arrangement results in the securing of a parallel path current-carrying heater which is operable upon the occurrence of predetermined conditions to so alter the normal division of current between the two parallel paths that a considerable augmented heating effect is produced. Such an arrangement is especially suitable for use with higher current circuits wherein the problems of large biasing forces and corona become particularly severe.

The disk 75 is adapted to close the lower end of each type of refill unit, and since the passage 63 through the ferrule 44 is substantially the same diameter as the disk, it offers no impedance to the outwardly flowing arc extinguishing gas during the operation of the device, the disk being held in position by the same fusible element which causes the operation of the breaker.

The fuse is shown in the closed circuit position in Fig. 1, and it will be noted that the main operating spring 19 is tensioned so as to bias the piston member 33 in the direction of the upper terminal member 7. This biasing force is transmitted through the plunger and must be entirely balanced by the fusible element 67. Upon the occurrence of an overload condition in the controlled circuit of sufficient magnitude and duration to cause the heat generated in the disk member 75 and transmitted to the fusible element 67 by means of the retaining rivet 71 to effect the fusing of that element, the lower end of the plunger 47 is released and that member is caused to move upwardly into the central arc passage 45 under the biasing action of the operating spring 19. An arc is immediately established between the lower end of the plunger 47 and the ferrule 44. This arc will practically instantaneously contact the lower end of the wire 85 thereby putting the conductors 83 and 85 within the smaller arc passage 49 in parallel with the arc. If the current to be interrupted is of small magnitude, the immediate result will be an extinction of the arc in the central passage at the first zero point, all of the current flowing through the conductors 83 and 85. Further upward movement of the plunger 47 will then result in a separation of the two wires 83 and 85 which are in slidable conductive relationship, and a second arc will be established within the smaller arc extinguishing passage 49. That passage is particularly adapted for extinguishing small arcs, and the outflowing superheated water vapor will cause a rapid cooling and extinguishing of the arc.

If the magnitude of the arc current is large it will cause an immediate fusing of the conducting means (the wires 83 and 85) within the smaller arc passage 49, and the arc will persist in the larger passage 45, although the extinguishing operation is essentially the same. The heat of the arc causes the boric acid lining 43 to evolve superheated steam which flows outwardly longitudinally of the arc through the throat opening 55, the opening 63 in the ferrule, and the continuation of that opening in the lower portion

of the terminal member 9 and the hollow cylindrical member 91. The disk member 75 is blown out of the opening through the lower end of the fuse tube immediately upon the generation of any appreciable gas pressure within the device.

The provision of two arc passages and means for establishing an arc in each of those passages is an important feature of my invention in securing satisfactory operation of the device over a wide range of arc currents. This results from the fact that a sufficient evolution of arc extinguishing gas from the boric acid lining member of the two arc passages is secured only when the arc is brought into intimate contact with the inner surface of those passages. Thus if a low current arc were drawn into the larger of the arc passages, it would probably exist for an indefinite period of time due to the fact that insufficient gas would be evolved to effect its extinguishment. And while satisfactory interruption of low current arcs is secured within a small diameter arc passage, it is impossible to secure satisfactory interruption of heavy current arcs in such a passage, due to the fact that there is insufficient cross sectional area to permit all of the generated gas to vent without building up pressures within the passage capable of causing severe damage to the entire device.

The operation of the modification shown in Fig. 3 is essentially the same as the operation of the structure shown in Fig. 2, except that the first step in the circuit interrupting operation is the fusing of the link 95 which is connected in parallel with the current-carrying heater (the disk 75). The fusion of this link 95 causes substantially all of the current flowing through the interrupter to flow through the heater disk 75, thereby greatly increasing the internal heating produced therein. This additional heat is practically immediately transmitted to the fusible element 67 by means of the plunger retaining rivet 71 and causes the fusing of the junction between that member and the fusible element itself, thereby permitting the operating spring 19 to move the plunger to the open circuit position.

Following each circuit interrupting operation of the fuse, it is necessary to restore the device to an operative condition. This is accomplished, in the preferred embodiment of my invention, by the replacing of the refill element 37 thereby renewing all of the parts of the fuse which come in contact with the arc and which may be damaged thereby. The refill element 37 is relatively inexpensive, however, due to its simple structure, and while it makes possible the restoration of the fuse to a potential effectiveness equal to that when new, the cost of so doing is much less than the cost of restoring any of the previously known high-interrupting-capacity high-voltage fuses to an operative condition.

In the open circuit position, the plunger member 47 has been moved by the operating spring 19 a sufficient distance to draw the lower end of the plunger to the top of the central arc extinguishing passage 45. The first step in the insertion of a new refill element consists in the unscrewing of the threaded annular retaining member 97 which engages the threaded portion 96 of the lower terminal member 9. The fibre tube 41 which forms the body portion of the refill element 37 and its attached ferrule 44 are then free to drop out leaving only the plunger 47 within the fuse tube 1. In order to remove the plunger and re-insert the new refill element, the cap member 21 on the upper terminal 7 is unscrewed, move-

ment of the upper support member 27 being prevented by the pin 99 which engages suitable slots (not shown) in the annular member 17. The upper supporting member 27, the operating spring 19, the piston member 33, and the plunger member 47 are then free to drop out the lower end of the tube.

The next step is the unscrewing of the plunger member 47 from the piston member 33. Following this, a new refill element 37 is screwed securely into the piston member 33, the pin 79 preventing rotation of the plunger 47 with respect to the body portion of the refill element. The connected refill element and the plunger mechanism are then inserted in the lower end of the tube 1, and the cylindrical retaining member 97 is tightened so as to securely hold the ferrule 44 of the refill element 37 against the cooperating annular shoulder 101 of the lower terminal 9.

In order to tension the spring 19, it is necessary to insert a means for engaging the spring supporting member 27 into the fuse through the opening in the upper annular portion 17, the simplest device for effecting this being a rod having a suitable threaded end for engaging the threaded hole 103 in the top of the supporting member 27. This rod or other means is screwed into the threaded opening 103 and the spring supporting member 27 is then pulled upwardly toward the top terminal member 7. The pin 99 is aligned with the means which prevents the upper support member 27 from turning with respect to the tube itself, and this means also serves to hold the support member in the upper position while the cap member 21 is screwed on. The upper portion of the fuse tube is thus effectively closed and the entire device has been restored to an operative condition.

Particular attention is directed to the physical dimensions of the fusible element and the heater means therefor. Both are of such size that injurious corona formation will not occur at the voltages of the circuits on which these devices are ordinarily used, and in addition, the heater-fuse combination possesses sufficient thermal capacity to permit the device to carry heavy overload currents for short periods without in any way decreasing the ability of the device to function upon the occurrence of prolonged low current overloads.

It will thus be seen that I have disclosed an improved high voltage expulsion fuse which is particularly suitable for use on very high voltage circuits through which low magnitude currents normally flow.

In addition, it will be seen that I have disclosed an improved refill element for use with expulsion fuses which permits the replacement, at a very moderate cost, of all of the parts of the fuse which are exposed to the action of the arc. Further, I have disclosed means whereby a fusible element possessing considerable mechanical strength and sufficient large physical dimensions to prevent any injury thereto as a result of corona formations may be utilized on very low current circuits.

Besides these features capable of wide adaptation to the expulsion fuse art, I have disclosed certain specific forms of construction which are particularly effective in carrying out the general objects of my invention. One of these forms is an improved heater means for the fusible element of a circuit interrupter which utilizes a current carrying element of non-metallic resist-

ing material and conducting means in intimate contact therewith for transmitting the heat generated to the fusible element.

Another of these improved forms is a heater for a thermally responsive fusible element which utilizes a current carrying electro-responsive device in parallel with the heater for increasing the normal heating effect thereof upon the occurrence of predetermined conditions.

While, in accordance with the patent statutes, I have given the foregoing details of a preferred practical embodiment of my invention, it is to be understood that many variations from the precise form described are possible and may for some applications be desirable. I desire, therefore, that the language of the accompanying claims shall be accorded the broadest reasonable construction and that my invention be limited only by what is explicitly stated in the claims and by the prior art.

I claim as my invention:

1. In a circuit interrupter, means for defining the walls of an arc chamber, a rigid plunger means movable within said arc chamber to a closed circuit position and to an open circuit position, means biasing said plunger means toward the open circuit position, thermally responsive means for restraining said plunger means in the closed circuit position, against said biasing means, and means for heating said thermally responsive means comprising a current carrying heater and an electro-responsive means for limiting the current in said heater except upon the occurrence of predetermined electrical conditions.

2. In a circuit interrupter, means for defining the walls of an arc chamber, conducting means movable within said arc chamber to a closed circuit position and to an open circuit position, spring means biasing said movable means toward the open circuit position, thermally responsive means for restraining said movable means in the closed circuit position against said biasing means, and heater means for causing said thermally responsive means to release said movable means, said heater means comprising a current-carrying heater unit and a current-carrying electro-responsive unit, normally connected in parallel with said heater unit, for limiting the current flow in said heater unit until the occurrence of predetermined electrical conditions.

3. In a circuit interrupter, means for defining the walls of two connecting chambers, means movable within one of said chambers to a closed circuit position and to an open circuit position, spring means disposed within the other of said chambers for biasing said movable means toward the open circuit position, fusible thermally responsive means for restraining said movable means in the closed circuit position against said biasing means, and heater means for causing the release of said movable means, said heater means comprising a current-carrying heater unit, and a current-carrying fusible element, normally connected in parallel with said heater unit, for limiting the current flow in said heater unit until the occurrence of predetermined electrical conditions.

4. In a circuit interrupter, tubular means for defining the walls of an arc chamber, a rigid plunger means movable within said arc chamber to a closed circuit position and to an open circuit position, means biasing said plunger means toward the open circuit position, fusible thermally responsive means disposed within said arc chamber for restraining said plunger means in the

closed circuit position against said biasing means, and means for heating said fusible means comprising a current-carrying heater unit and a current-carrying electro-responsive unit connected in parallel with said heater means, said electro-responsive unit operating upon the occurrence of predetermined conditions to cause an increase in the normal heating effect of said heater unit.

5. In an electro-responsive device, a fusible element and a heater means therefor comprising a current carrying body of non-metallic resistance material, means extending through said body for conducting the heat generated therein to said fusible means, and a current-carrying electro-responsive means connected in parallel with said current-carrying body of resistance material, said electro-responsive means acting upon the occurrence of predetermined conditions to so change the normal division of current flow between said 20 parallel paths so that a substantially greater than normal proportion of the current flows through said resistance unit.

6. In an electro-responsive device, a fusible element, and a heater means therefor comprising a current-carrying body of non-metallic resistance material, means extending through said body for conducting the heat generated therein to said fusible means, and a current-carrying fusible means connected in parallel with said current-carrying body of resistance material, said means being fusible upon the occurrence of predetermined conditions to cause substantially all of the current flowing through said device to flow through said body of resistance material.

35 7. In a circuit interrupter, tubular means at least partially of insulating material, a cap means of conducting material for closing one end of said tubular means, a means of conducting material supported at the other end of said tubular means 40 in such manner that at least a portion of the central passage through said tubular means will be open, means supported on said cap means and movable within said tube to open the circuit, means biasing said movable means to the open 45 circuit position, and means for retaining said movable means in the closed circuit position against said biasing means, said retaining means comprising a fusible means, and a member of non-metallic resistance material which is adapted 50 to be held against said tube and said conducting means by said biasing means in such manner that said tube is releasably closed when said interrupter is in the closed circuit position.

8. In a circuit interrupter; tubular means, at least partially of insulating material; conducting means supported adjacent one end of said tubular means; fusible means within said tubular means; and means for substantially closing one end of said tubular means and for electrically connecting said fusible means with said conducting means, said means comprising a heater means for causing the fusion of said fusible means upon the occurrence of predetermined conditions, and having proper dimensions for closing one end of said tubular means; said connecting means being normally retained in position by said fusible means but being movable upon the fusion of that means to open one end of said tubular means.

9. In a circuit interrupter; tubular means for defining an arc passage, at least a portion of which is lined with a material capable of evolving an arc extinguishing gas when placed in proximity to an electric arc; conducting means movable through said arc passage to establish an arc 75 therein; fusible means for controlling the opera-

tion of said arc drawing means; and heater means for causing the fusion of said fusible means upon the occurrence of predetermined conditions, said heater means being normally adapted to close one end of said arc passage and being movable, 5 during the circuit interrupting operation, to open at least a portion of one end of said arc passage in order to permit the venting of the gas evolved from said lining.

10. In a circuit interrupter; tubular means for defining an arc passage, at least a portion of which is lined with a material capable of evolving an arc extinguishing gas when placed in proximity to an electric arc; conducting means movable through said arc passage to establish an arc 15 therein; fusible means for controlling the operation of said arc drawing means; and heater means for causing the fusion of said fusible means upon the occurrence of predetermined conditions, said heater means comprising a member of non- 20 metallic, resistance material which is so proportioned that it normally closes one end of said arc passage and which is movable, during the circuit interrupting operation, to open one end of said arc passage in order to permit the venting of the 25 gas evolved from said lining.

11. In a circuit interrupter; tubular means for defining an arc passage, at least a portion of which is lined with a material capable of evolving an arc extinguishing gas when placed in proximity to an electric arc; means for closing one 30 end of said tubular means; spring biased, conducting means movable through said arc passage to establish an arc therein; fusible means for preventing movement of said arc drawing 35 means except upon the occurrence of predetermined conditions; and a current-carrying heater means, thermally conductively disposed with regard to said fusible means, for causing the fusion thereof upon the occurrence of predetermined 40 conditions; said heater means being so proportioned that it normally closes one end of said arc passage, being held in that position by said spring biased, arc drawing means, and being movable, during the circuit interrupting operation, to open one end of said passage in order 45 to permit the venting of the gas evolved from said lining.

12. In an expulsion circuit interrupter; tubular means for defining an arc passage, at least 50 a portion of which is lined with a material capable of evolving an arc extinguishing gas when placed in proximity to an electric arc; means for closing one end of said arc passage, the other end of said arc passage being open during the 55 circuit interrupting operation; a spring biased, plunger means movable through said arc passage to establish an arc therein; fusible means for normally restraining said arc drawing means in the closed circuit position; and current-carrying 60 heater means for causing the fusion of said fusible means upon the occurrence of predetermined conditions; said heater means comprising a substantially non-inductive resistance element, being so proportioned that it substantially 65 closes said other end of said arc passage, except during the circuit interrupting operation, being held in that position by the reaction forces exerted by said spring biased plunger, and being adapted to be moved in the opposite direction 70 to that in which said arc drawing plunger is moved, during the circuit interrupting operation, by the gas evolved from said lining; said movement of said heater means causing said other end of said arc passage to be opened so as 75

to permit substantially free venting of said gas.

13. In a circuit interrupter; tubular means for defining an arc passage; means for closing one end of said arc passage; a conducting seat positioned at the other end of said passage; means, including a spring biased fusible element, for drawing an arc within said arc passage during the circuit interrupting operation; and a substantially non-inductive, current-carrying, heater means for causing the fusion of said fusible element upon the occurrence of predetermined conditions, said heater means including a member of non-metallic resistance material which is held against said seat by the reaction forces of said spring biased arc drawing means.

14. In a circuit interrupter; tubular means for defining an arc passage; means for closing one end of said arc passage; a conducting seat positioned at the other end of said passage; means, including a spring biased fusible element, for drawing an arc within said arc passage during the circuit interrupting operation; and a substantially non-inductive, current-carrying, heater means for causing the fusion of said fusible element upon the occurrence of predetermined conditions, said heater means including a member of non-metallic, resistance material, having a passageway therein, which is adapted to be held again said seat by the reaction forces of said spring biased arc drawing means, said reaction forces being transmitted to said resistance member through the agency of a conducting means, having an enlarged head portion, which means extends through said passageway and serves to conduct the heat generated within said resistance element to said fusible arc drawing means.

15. In a circuit interrupter, conducting means movable from a closed circuit position to an open circuit position to open the electrical circuit through said interrupter, means biasing said movable means to the open circuit position, and electro-responsive means for normally holding said movable means in the closed circuit position against said biasing means, said holding means including a fusible element, heater means for said fusible element comprising a hollow member of resistance material, and a means of conducting material which extends through said hollow heater member for mechanically and thermally connecting said fusible element and said heater, said means of conducting material having an enlarged head portion for engaging said heater, and both said fusible element and said heater being subjected to substantially all the force of said biasing means.

16. In a circuit interrupter, conducting means movable from a closed circuit position to an open circuit position to open the electrical circuit through said interrupter, tension spring means biasing said movable means to the open circuit position, and electro-responsive means for normally holding said movable means in the closed circuit position against said biasing means, said holding means including a fusible element, heater means for said fusible element comprising a hollow member of non-metallic resistance material, means for supporting said heater member, and a rod-like member of conducting material which extends through said hollow heater member for mechanically and thermally connecting said fusible element and said heater, said rod-like member having an en-

larged head portion for engaging said heater, and both said fusible element and said heater being subjected to substantially all the force and of said biasing means.

17. In a circuit interrupter, tubular means for defining an arc passage, a seat positioned at one end of said tubular means, means movable from a closed circuit position to an open circuit position to open the electrical circuit through said interrupter and establish the arc incident thereto within said arc passage, means biasing said movable means to the open circuit position, electro-responsive means including a fusible element for normally holding said movable means in the closed circuit position against said biasing means, and a heater means for causing the fusion of said fusible element upon the occurrence of predetermined conditions, said heater means including a member of resistance material which is held against said seat by the reaction forces of said biasing means.

18. In a circuit interrupter, tubular means for defining an arc passage, a conducting seat positioned at one end of said tubular means, means movable from a closed circuit position to an open circuit position to open the electrical circuit through said interrupter and establish the arc incident thereto within said arc passage, means biasing said movable means to the open circuit position, and electro-responsive means for normally holding said movable means in the closed circuit position against said biasing means, said holding means including a fusible element, heater means for said fusible element comprising a hollow member of resistance material, and a means of conducting material which extends through said hollow heater means for mechanically and thermally connecting said fusible element and said heater, said heater means being adapted to engage said seat and being normally held against said seat by the reaction force of said biasing means which force is transmitted thereto by said means of conducting material.

19. In a circuit interrupter, tubular means for defining an arc passage, a conducting seat positioned at one end of said tubular means, conducting means movable from a closed circuit position to an open circuit position to open the electrical circuit through said interrupter to establish the arc incident thereto within said arc passage, resilient means biasing said movable conducting means to the open circuit position, and electro-responsive means for normally holding said conducting means in the closed circuit position against said biasing means, said electro-responsive means including a fusible element, heater means for said fusible element comprising a hollow member of non-metallic resistance material, and a means of conducting material having a body portion which extends through said hollow heater means for mechanically and thermally connecting said heater and said fusible element, at least the edge portions of said heater member engaging said conducting seat, said means of conducting material having an enlarged head portion for engaging said heater adjacent the central opening therethrough, and said heater being held in engagement with said conducting seat by the reaction force of said resilient biasing means which force is transmitted thereto by said means of conducting material.
